Primary Examiner — Michael A Pratt(74) *Attorney, Agent, or Firm* — Lerner, David, Littenberg, Krumholz & Mentlik, LLP(57) **CLAIM**

The ornamental design for a sling for archery bow, as shown and described.

DESCRIPTION

FIG. 1 is a perspective view of one embodiment of the sling for archery bow, in accordance with the present invention;

FIG. 2 is a front elevation view of the embodiment shown in FIG. 1;

FIG. 3 is a rear elevation view of the embodiment shown in FIG. 1;

FIG. 4 is a right side elevation view of the embodiment shown in FIG. 1, the left side being a mirror image thereof; and,

FIG. 5 is a top plan view of the embodiment shown in FIG. 1. The archery bow depicted in FIG. 1 is shown in broken line for environmental purposes only and as such forms no part of the claimed invention. Certain aspects of the sling for archery bow are shown in broken line for illustrative purposes only and as such form no part of the claimed invention.
